UNITED STATES PATENT OFFICE.

HARRY J. BARNHART, OF MARION, OHIO, ASSIGNOR TO THE OSGOOD COMPANY, OF MARION, OHIO, A CORPORATION OF OHIO.

TRACK LINKS FOR STEAM-SHOVEL STRUCTURE.

Application filed November 3, 1921. Serial No. 512,519.

To all whom it may concern:

Be it known that I, HARRY J. BARNHART, a citizen of the United States of America, residing at Marion, in the county of Marion 5 and State of Ohio, have invented certain new and useful Improvements in Track Links for Steam-Shovel Structure, of which the following is a specification.

My invention relates to track links for 10 steam shovel structure and has to do especially with that class of steam shovels having traction units of the endless traction type. It contemplates the provision of a novel type of tread for the traction units 15 which is especially designed and constructed to provide spaces through which the dirt and other extraneous material may pass to the atmosphere, thus avoiding packing of this extraneous material in the sockets with 20 which the teeth of the driving sprockets contact.

My novel type of tread member is further equipped with guides that are relatively independent of the sockets which receive the 25 sprocket teeth and that are, therefore, free from any wear resulting from contact with these sprocket teeth. Previous devices in the art have attempted to rely on the sprockets for guidance, to provide flanges on the 30 supporting rolls and to use guide flanges which also serve as means cooperating with the sprocket teeth to effect driving. These devices have not been effective and I have discovered that by using guide flanges which 35 are independent of the sprocket teeth, the operation of the driving chain is much more effective. For one reason, when the guide flange is used to serve also as a portion of the driving surfaces the wear upon this 40 guide flange will eventually unfit it for either driving or guiding.

Another feature of my device has to do with the provision of an overlapping structure between the tread units which more effectively serves to exclude the mud and dirt that would otherwise have a tendency to work into the space between such units. This is effected by the provision of flanges upon the lateral edges of the tread units 50 which have such an interfitting relation as to permit a free movement of the tread units to every necessary extent but at the same time to practically cover the crevices between adjacent tread units.

55 The preferred embodiment of my inven-

tion is shown in the accompanying drawings wherein similar characters of reference designate corresponding parts and wherein—

Figure 1 is a bottom plan view of one of my tread units.

Figure 2 is a side elevation of the structure shown in Figure 1.

Figure 3 is a section taken on line 3—3 of Figure 1.

Figure 4 is a section taken on line 4—4 of Figure 1.

In the drawings, my tread member is shown as formed entirely in one piece of metal. It comprises a table-like portion 1 with a flange 2 at one end and a flange 3 at the opposite end. Centrally disposed upon the inner side of this table-like portion 1 is an integral formation 4 which is provided with a socket aperture 5 extending entirely through the integral formation and the table-like portion. Upon opposite sides of this aperture or socket 5 are flanged members 6 and 7 which extend upwardly as shown in Figures 2 and 4 to form guide members with their coaction with the supporting rolls for the tread units. These flanges or guides 6 and 7 are braced against lateral pressure by means of integral flanges 8 and 9 formed upon the inner sides of the table-like portion 1 and extending at right angles to the guides 6 and 7.

An important aspect of my invention has to do with the provision of apertures 10, 11, 12 and 13 upon opposite sides of the sockets 5. These apertures preferably each lead to the atmosphere as, for example, the aperture 12 is connected with the atmosphere by means of the passageway 14 and the outer aperture 15, as best shown in Figure 3, while the aperture 11 is connected to the atmosphere by means of the passageway 16 and the outer aperture 17. The aperture 10 is provided with a passageway and outer aperture similar to the aperture 11 while the aperture 13, which is disposed opposite the aperture 12, is provided with a similar passageway but with a much larger outer aperture as is clearly shown in Figure 3. The result is that openings are provided on all sides of the sockets which permit the free passage of dirt and other extraneous material to the atmosphere. This is in addition to the free passage which is permitted from the base of the tooth socket through the outer surface of the table-like portion 1.

110

It will be seen that I have provided a simple one-piece metal tread unit structure wherein the guide flanges are positioned to guide the traction units independent of the 5 tooth sockets and wherein these tooth sockets are provided with outwardly extending passages through which the dirt may pass at will.

Having thus described my invention, what 10 I claim is:

1. In steam shovel structure, traction units comprising tread members, tooth sockets in said tread members, said sockets having passageways leading therefrom, guides independent of said sockets, and overlapping flanges on said tread members.

2. In steam shovel structure, traction units comprising integral tread members having sockets, said sockets having openings, said tread members having openings leading to the atmosphere and connecting with the openings in said sockets.

3. A track link comprising a base, a housing on said base, said housing forming a tooth socket, said housing having laterally extending openings and an opening extending through said base, and said housing

having upstanding flanges on either side thereof.

4. A track link comprising a base, an 30 integral housing on said base, said housing forming a tooth socket, said housing comprising four walls, and open at both ends, each of said walls having openings therein communicating to the atmosphere, and 35 upstanding flanges on said housing, said flanges extending oppositely from said base, brace members extending from said flanges to said base.

5. A track link comprising a base, a housing on said base, said housing having a 40 socket aperture in one end, and having an opening opposite said socket aperture, said housing comprising walls, having openings 45 communicating to atmosphere, upstanding flanges on said housing and extending oppositely from said base, brace members connecting said flanges with said base, said brace members integral with said flanges and base. 50

In testimony whereof I hereby affix my signature.

HARRY J. BARNHART.
